JOSEPH S. REYNOLDS, OF LONG BEACH, CALIFORNIA.

ROTARY SCRAPER WITH AUTOMATIC ELEVATING CONTROL.

Application filed February 24, 1925, Serial No. 11,153. Renewed June 21, 1927.

This invention relates to rotary scrapers such as are employed for leveling land.

The common type of rotary scraper comprises a scoop having a draft frame attached therewith by which it is drawn over a surface to be leveled. This scoop is drawn over the surface with a cutting edge thereof in engagement. When the scoop is full, a scoop control mechanism is operated in such a manner as to remove the cutting edge from digging position into a non-digging or carrying position. The scraper is then drawn to a suitable dumping place where the control mechanism is further operated so as to permit a dumping of the accumulated dirt.

In the general type of rotary scrapers, such control mechanisms are hand-operated, being actuated by the driver of a tractive vehicle of the scraper. These hand controlled operating mechanisms are very successful in small scrapers, being easily handled by the operator; however, when such arrangements are employed on large capacity scrapers, it is found that hand-operating control mechanisms are very impractical, owing to the fact that it requires more than a man's strength for operation thereof.

It is an object of my invention to provide a rotary scraper of the character mentioned in which the weight of the load carried by the scoop of the scraper will assist in removing the scoop from digging position into carrying position.

It is another object of my invention to provide a rotary scraper of the character mentioned in which the weight of the load carried by the scoop will automatically remove the scoop from digging position into carrying position.

It is a still further object of my invention to provide a rotary scraper having a scoop control mechanism which may be adjusted so that the scoop will be removed from digging position into carrying position when any desired load is accumulated in the scoop.

The rotary scraper of my invention includes a scoop which is rotatably attached to a suitable draft frame. For controlling the position of the scoop, a scoop control mechanism is provided. Associated with the

scoop control mechanism is a means whereby said mechanism will be operated in such a manner as to remove the scoop from digging into carrying position when the load carried by such scoop reaches a certain point. Associated with the scoop control mechanism is a means for varying the load at which the mechanism will be operated.

It is another object of my invention to provide in a rotary scraper a control mechanism which will have a controlling engagement with the scoop in such a manner that strains upon the scoop will be reduced to a minimum.

In the ordinary type of scraper known to the inventor, the control mechanism is engageable with the scoop near each end thereof. It is found that these engagements do not always release at the same time. Releasing of one engager prior to the releasing of another allows one end of the scoop to partially rotate while the other remains in position. This causes great strains in the scoop and its connected parts distorting them and causing a rapid destruction thereof. My invention by providing a single engagement near the center of the scoop eliminates all these disadvantages.

Other objects and the salient advantages of this invention will be made evident hereinafter.

Referring to the four sheets of drawings in which I illustrate my invention,

Fig. 1 is an elevational view of a rotary scraper embodying the features of my invention, this view showing the scoop control mechanism in digging position.

Fig. 2 is an elevational view of the rotary scraper shown in Fig. 1, this view showing the scraper in carrying position.

Fig. 3 is a plan view of Fig. 2.

Fig. 4 is an enlarged fragmentary sectional view of the forward end of the rotary scraper taken substantially on the line 4-4 of Fig. 2.

Fig. 5 is an enlarged fragmentary view showing the position of the rotary scraper when it is in carrying position.

Fig. 6 is an enlarged fragmentary sectional view of a portion of the control mechanism of my invention, this view showing

clearly the latch construction and means for releasably locking the latch bar of my invention in an elevated position.

Fig. 7 is a fragmentary sectional view taken substantially on the line 7—7 of Fig. 5.

Fig. 8 is a plan view of the fragmentary showing of the scoop control mechanism in Fig. 6.

Fig. 9 is an elevational view of my invention applied to a wheeled rotary scraper.

With reference to Figs. 1 to 8, inclusive, of the drawings, a preferred form of my invention is embodied in a rotary scraper having a scoop 11 and a draft frame 12. The scoop 11 is of customary construction having a bottom 14 which provides a forward cutting edge 15, a back 16 and sides 17. At each end of the scoop a runner 17^a is secured as shown. The draft frame of my invention provides side bars 18 which extend parallel to the sides 17 of the scoop 11 and pivot thereto by means of trunnions 19. The side bars 18 are directed diagonally inward at 20 and conjoin with a central bar 21 at the forward end thereof, as clearly shown in Fig. 4. The forward ends of the side bars 18 and the central bar 21 are secured together between plates 24 by bolts 25. Adjacent to the point 20 at which the

side bars 18 are directed inwardly, a cross bar 27 is secured by suitable bolts 28 extending through the ends of the cross bar 27 and the side bars 18. The rear end of the central bar 21 is secured, as indicated at 30, to the cross bar 27. Secured to the scoop 11 in substantially a central position is a central stop bar 35 which carries a loading stop 36, a spreading stop 37 and a travelling stop 38.

In the drawings I show the loading stop 36 in engagement with an engager 40 carried on a shaft 41 which extends between the rear ends 42 of arms 43 which form a part of a latch bar 44. The forward end of the latch bar 44 pivots at 45 to a dump lever 46, this dump lever 46 pivoting to the central bar 21 at 47. The rear end of the latch bar 44 is supported by links 48 which pivot on a pin 49 carried by the arms 43. The upper ends of these links 48 are pivotally secured on a pin 51 which is carried by plates 53 of a loading lever 54. This loading lever 54 is pivotally secured to uprights 55 by a pin 56 extending through the uprights 55 and through the plates 53 of the loading lever 54. The uprights 55, as clearly shown in Fig. 6, are secured by bolts 57 to the cross bar 27.

Pivoted to one side of the central bar 21, as clearly shown in Fig. 6, is a dog 60, this dog pivoting on a pivot 61 carried by the central bar 21. The upper end of the dog 60 has a tension spring 62 attached thereto at 63. The forward end of the spring 62 is connected to adjustment links 64 by a pin

65 extending through one of the series of holes 66. The adjustment links 64 pivot at 67 to a plate 68 which forms a part of the latch bar 44. The dog 60 is restrained from moving forwardly beyond the position shown in the drawings by a lug 70 which engages the cross bar 27, as clearly illustrated in Fig. 6. The spring 62 exerts a pull upon the latch bar 44 and resiliently retains it in the position shown in the drawings. In other words, the spring 62 retains the latch bar in latching position or in such a position that it will engage a stop of the scoop. The tension of the spring may be adjusted by extending the pin 65 through other of the holes 66 of the links 64.

The latch bar is removed from latching position by an actuation of the dump lever 46. This dump lever 46 has a rope 73 attached to the upper end thereof which extends forwardly to a tractor 74, which is for pulling the rotary scraper. The driver of the tractor exerts a pull upon the rope 73, swinging the dump lever 46 forwardly into the position indicated by dotted lines 75 of Fig. 6. This moves the latch bar 44 into unlatching position, thus disengaging the engager 40 and a stop carried on the stop bar 35.

The latch bar 44 is removed from depressed position, such position being shown in Fig. 1 and by dotted lines 77 in Fig. 6, into elevated position, such positions being shown in full lines in Figs. 2, 3, 5, 6, 7 and 8 by an actuation of the loading lever 54. The upper end of the loading lever 54 has a rope 76 secured thereto which extends forwardly to the tractive vehicle 74. The rope 76 serves as a manual means for swinging the lever 54 forwardly; however, my invention provides an automatic means for swinging the lever 54, as will be described later on. By swinging the lever 54 from the position shown in Fig. 1 or by the dotted lines 78 of Fig. 6 into the position shown in full lines in Fig. 2 and Fig. 6, the latch bar 44 is moved from the dotted line position 77 in Fig. 6 into the full line position shown in this figure, that is, the latch bar is moved from depressed into elevated position. When the lever 54 is swung forwardly as shown by the full lines in Fig. 6, it pivots on the pivot 56 and lifts the links 48 upwardly. This in turn elevates the rear end of the latch bar 44. The elevated position of the latch bar 44 is governed by the engagement of extending ends 80 of the pin 51 with stop formations 81, as shown clearly in Figs. 5, 6, 7 and 8, which are formed at the upper end of the uprights 55.

My invention provides a means for positively retaining the latch lever in elevated position and consequently the scoop in carrying position until the dump lever 46 is actuated. On the forward face of the dog 60

is a projection 83 providing a shoulder 84 and an inclined face 85. A pin 88 is carried by the latch bar 44. As the latch bar 44 is moved into elevated position, the pin 88 engages the inclined face 83, swinging the dog 60 rearwardly until the pin 88 passes thereby, at which time the dog returns to the position shown in Fig. 6, and the pin 88 will rest on the shoulder 84. The latch bar by this construction is positively retained in upper position until the dump lever 46 is actuated. When the dump lever 46 is actuated, the latch bar 44 moves forward to the extent that the pin 88 is removed from engagement with the shoulder 84. The parts are proportioned, however, so that the engager 40 disengages with a stop of the scoop previous to the disengaging of the pin 88 and the shoulder 84. This arrangement is provided so that the latch bar 44 and the associated mechanism will not be swung into lower position by the weight of the load carried by the scoop as this might result in much damage to these parts.

The means for automatically actuating the scoop control mechanism includes a tilting bar 95 which is pivotally secured by a bolt 96 extending through a hole 97 in the rear end of the bar 95, and extending through the plates 53 of the loading lever 54, as clearly shown in Figs. 6, 7 and 8. This tilting bar 95 extends forwardly from the loading lever 54 and is connected to the upper end of an actuating lever 98 by means of a pin 99 extending through a slot 100 formed in the forward end thereof. This actuating lever 98 forms a part of an intermediate member 103 and has plates 104 secured at the lower end thereof, as shown in the drawings.

The intermediate member 103 pivots by a bolt 105 to the plates 24. The plates 104 of the intermediate member 103 have openings 106 through which a rod 107 extends for securing the link 108 of the tractive vehicle 74 thereto. The rotary scraper is drawn over the ground by the tractive vehicle 74 and is pulled by means of the intermediate member 103. At 110 there connects to the intermediate member a tension spring 111. A rearward end of the tension spring 111 connects to a member 112 which extends through a bracket 113 secured to the central bar 21. A nut 115 is threaded on the end of the member 112, which nut is advanced or retracted thereon for varying the tension in the spring 111. The spring 111 is provided for the purpose of resiliently retaining the intermediate member in the position shown in Fig. 1 of the drawing. When the member 103 is moved into the position shown in Fig. 2, the tilting bar 95 is pulled forwardly, thus exerting a pull upon the dumping lever 54 which actuates the latch mechanism in the same manner as would a pulling upon the rope 76.

A complete operation of this modification of my scraper is substantially as follows:

Considering the rotary scraper in digging position, as shown in Fig. 1 of the drawings, it will be seen that the cutting edge 15 of the scoop 11 is in engagement with the surface of the ground. The scraper is drawn along the ground by a tractive vehicle 74, the pull upon the frame 12 being transferred through the intermediate member 103. As the scoop moves over the ground, a load of dirt is gradually accumulated. As this load accumulates, the force necessary to drag the scraper increases, that is to say, as the weight of the load carried in the scraper increases, the opposition to pulling is greater, and the force necessary to pull the scraper is greater.

From the drawings it will be seen that the link 108 secures to the intermediate member 103 eccentric with respect to the pivot 105 thereof. For this reason, as the scraper gathers dirt and the weight of the load carried thereby increases, the intermediate member 103 will swing forwardly with respect to the frame 12 in opposition to the action of the spring 111. When the intermediate member has moved to the extent shown in Fig. 2, the actuator lever 98 will have pulled the tilting bar 95 forwardly sufficient to swing the loading lever 54 into elevated position, that is, in such a position that the pin 51 engages the stops 81 and the latch bar 44 is retained in elevated position by the pin and dog cooperation. The movement removes the scraper into carrying position, and it is obvious from Fig. 2 that at this time the cutting edge 15 of the scoop 11 is out of engagement with the surface of the ground, and the scoop is dragging on the back portion of the bottom 14 thereof. As the intermediate member 103 swings forwardly, it lifts the forward end of the frame 12 which assists in removing the cutting edge 15 from engagement with the ground.

The rotary scraper is then pulled into carrying position to a suitable dumping place where the dumping lever is actuated by a pull upon the rope 73. This, as previously explained, pulls forwardly upon the latch bar 44, causing a disengagement between the stop 36 and the engager 40 and allowing a rotation of the scoop 11. If it is desired to dump the contents of the scoop in a pile, the latch bar is retained in disengaging position until the stop 37 has passed thereby. It is then allowed to return to engaging position and will engage the stop 38, thus retaining the scoop 11 in travelling position. When it is desired to gather more dirt, the actuator bar is moved into disengaging position by an actuation of the dumping lever 46, allowing the stop 38 to pass thereby, after which the latch bar returns to latching position so that the stop 36 will be engaged. If it is desired to

spread the dirt when it is dumped, the latch bar is removed only while the stop 36 passes thereby and is returned so that it will engage the stop 37. This permits the scoop 11 to swing a partial rotation and the cutting edge 15 thereof is utilized to spread the dirt over an area.

The automatic dumping arrangement of the invention may be adjusted so that it will actuate the different loads carried in the scoop 11. This is accomplished by regulating the tension of the spring 111 by advancing or retracting the nut 115 on the member 111. The depressed position of the latch bar 44 is controlled by the engagement of the actuating bar 98 of the intermediate member 103 with the forward end of the central bar 21, this engagement being shown clearly in Fig. 1. To adjust the depressed position of the latch bar 44, it is necessary to alter the effective length of the tilting bar 95. This is accomplished by passing the bolt 96 through a different hole 97 in the rearward end of the bar 95.

In the drawing the mechanism is shown having an automatic operation of the latch mechanism. To utilize the pull of the tractor for merely assisting in the operation of the mechanism, it is necessary to pass the bolt 96 connecting the tilting bar 95 to the loading lever 54 through openings 120. As is obvious, this shortens the effective lever arm of the tilting bar 95 on the loading lever 54, diminishing the moment of force applied to the loading lever. When the parts are in this position, the automatic mechanism will not entirely remove the scoop into carrying position, and it is necessary to actuate the lever 54 by the rope 76.

On light materials, the weight of the load when the scraper is full is not equal to the weight of a load of heavier material. To compensate for this, I provide a lower opening 121 through each of the plates 104 of the intermediate member 103 through which the bolt 107 may be passed for connecting the link 108 to the intermediate member 103. This varies the effective lever arm and compensates for the change in weight per unit volume of the dirt being carried.

The scraper shown in Figs. 1 to 8 inclusive, and just described, has proven to be very successful. The automatic mechanism works very successfully and is very valuable on large scrapers on which it is practically impossible to operate the scoop control mechanism by hand without the use of mechanical screws, etc. which render the actuation of the mechanism very slow. A scraper embodying the features of my invention requires considerably less attention than the hand-operated scoop control mechanisms.

In actual practice I have found that it is not absolutely necessary to provide the dog

60 for locking the latch 44 in elevated position. If the load carried by the scoop is sufficient, the weight of the load retains the scoop, through the mechanism described, in carrying position. Sometimes a portion of the load is lost. When this occurs the scoop, when the dog 60 is not provided, automatically returns to digging position and regains the lost weight.

In Fig. 9 of the drawing I show the features of my invention applied to a wheeled rotary scraper. In this figure the construction is identical with that of the scraper shown in the other view of the drawings, except for the addition of a few parts. Identical parts in Fig. 9 will have the same figures as those parts in the other figures of the drawings. In this modification I extend the side bars 18 rearwardly somewhat beyond the scoop 11, as indicated at 130. Extending between the rearward ends 130 of the side bars 18 is a crank shaft 131 having wheels 132 carried thereby which are eccentrically carried with respect to the bearings 133 of the shaft 131. Extending upwardly from the shaft 131 is a lever 134, this lever 134 being connected by a bar 135 to the loading lever 54.

In this modification the operation of the parts identical with the parts of the other modification of my invention is the same. When the scraper is removed from digging position into carrying position, the lever 54 is swung forwardly. This exerts a forward pull upon the link 135 which in turn pulls forwardly on the lever 134. The lever 134 rotates the crank shaft 131, swinging it in such a manner as to swing the wheels 132 downwardly with respect to the frame 12, as indicated by the dotted line position 136 of this figure. This movement elevates the rear end of the frame 12 and lifts the scoop 11 entirely from engagement with the surface of the ground. In this construction the dragging of the scoop 11, when it is full, may be entirely done away with or may be partially relieved.

In the drawings I have shown my invention applied to a rotary scraper having a control mechanism which engages with stops on the scoop 11 only at central points. It should be understood, however, that my invention is not limited to the specific construction shown in the drawings but may be provided on scrapers using two points of engagement, one point at each end of the scoop as is customary in some constructions of scrapers.

I claim as my invention:

1. In a rotary scraper, the combination of: a draft frame; a scoop supporting one end of said draft frame to which said scoop pivotally attaches; a control mechanism for retaining said scoop in digging position; and an intermediate member pivotally se-

cured to said draft frame whereby said scraper is pulled, said intermediate member being associated with said control mechanism so as to operate said mechanism and 5 remove said scoop from digging into carrying position when said scoop is loaded.

2. In a rotary scraper, the combination of: a scoop; a draft frame pivotally secured to and supported at one end by said scoop; a 10 stop carried by said scoop; a latch bar carried by said draft frame, said latch bar being adapted to engage said stop, thus retaining said scoop in digging position; a loading lever associated with said latch bar and said 15 draft frame; and an intermediate member pivotally associated with said latch bar and pivotally secured to said draft frame whereby said scraper is pulled.

3. In a rotary scraper, the combination 20 of: a draft frame; a scoop pivotally supporting one end of said draft frame and adapted to be drawn thereby; a stop carried by said scoop; a latch bar carried by said draft frame, said latch bar being adapted to 25 engage said stop, thus retaining said scoop in digging position; a loading lever pivotally attached to said draft frame; and an intermediate member pivotally secured to said draft frame whereby said draft frame 30 is pulled, thus drawing said scoop, and pivotally connected to said latch bar for moving same.

4. In a rotary scraper, the combination 35 of: a scoop; a draft frame pivotally secured to and supported at one end by said scoop; a stop carried by said scoop; a latch means carried by said draft frame, said latch means being adapted to engage said stop, thus retaining said scoop in digging position; an intermediate member pivotally secured to said latch means and to said draft 40 frame whereby said scraper is pulled; and means for resisting a relative movement between said draft frame and said intermediate member.

5. In a scraper of the character described, the combination of: a draft device; a scoop pivotally supporting one end of said draft device and adapted to be drawn thereby; a 50 stop supporting member secured to said scoop substantially midway between the ends thereof; a stop secured to said member; and means mounted on said draft device for holding or releasing said stop so as to permit the scoop to be held in scraping position, or released to dumping position as may be desired; an intermediate member pivotally secured to said draft device whereby said scraper is pulled; and means for resisting a 55 relative movement between said draft device and said intermediate member.

6. In a rotary scraper the combination of: a scoop having digging and carrying positions; a draft frame supported at one end 60 by said scoop through which said scoop

may be pulled by a tractor, said frame being extensible by the tractive pull of said tractor when said pull reaches a certain value; the front end of said frame being raised by said extension thereof; means for 70 fixing said value; and means operated by the extension of said frame to move said scoop from digging to carrying position.

7. In a rotary scraper the combination of: a scoop having digging and carrying positions; a draft frame secured to and supported at one end by said scoop; a member pivoted to the front end of said frame; means for applying tractive pull to said frame through said member; and means, 75 actuated by said member when said tractive pull reaches a certain value, for moving said scoop from digging to carrying position.

8. In an automatic scraper control, the combination of a draft frame; a scraper bowl pivotally supporting one end of said draft frame; a hitch device pivotally secured at the forward end of the said draft frame and adapted to be secured to a draft implement; and means secured to the said pivotal hitch device and adapted to be actuated at a predetermined load within the said scraper for rotating the said scraper to a non-scraping position.

9. In an automatic scraper control, the combination of: a frame; a scoop pivotally supporting one end of said frame; and a draft connection pivotally secured to the said frame and adapted to operate at a predetermined load within the scraper to rotate the said scraper to a non-scraping position.

10. In an automatic scraper control, the combination of: a frame; a scraper pivotally supporting one end of said frame; an arm pivotally mounted on said frame; a latch bar associated with said frame; means connecting the said arm and said latch bar; and means secured to the said arm for connecting the said frame with a draft implement and operable at a predetermined load in the said scraper to actuate the said latch bar to engage the said scraper and to rotate the same to a non-scraping position.

11. In an automatic scraper control, the combination of: a frame; a scraper pivotally mounted within the frame and supporting one end thereof; means for connecting the said frame with a draft implement and operable at a predetermined load for rotating the said scraper in the said frame; and means for adjusting the said draft connecting means so as to regulate the load at which the said scraper is rotated.

12. In an automatic scraper control, the combination of: a frame; a scraper pivotally mounted in the frame and supporting one end thereof; latch means secured to the frame and adapted to be engaged with the said scraper for latching the said scraper in the scraping position; means pivotally 125

- connecting the said frame with a draft implement; means pivotally connecting the said last named means with the said latch means and operable at a predetermined load 5 for rotating the said scraper to a non-scraping position; and means associated with the said latch means for releasing the same to permit the scraper to rotate in the frame to dump the load.
- 10 13. In a scraper of the character described, the combination of: a draft device; a scoop pivotally supporting one end of said draft device and adapted to be drawn thereby; a stop supporting member secured to 15 said scoop substantially midway between the ends thereof; a stop secured to said member; means mounted on said draft device for holding or releasing said stop so as to permit the scoop to be held in scraping position, or released to dumping position as may be desired; and means pivotally secured to the draft device and adapted to operate at a predetermined load within the scoop to rotate the said scoop to a non- 20 scraping position.
14. In an automatic scraper control, the combination of: a frame; a scraper pivotally mounted within the frame; latch means secured to the frame and adapted to engage 25 the said scraper to hold the same in the scraping position; draft means secured to the said frame; means connecting the draft means with the said latch means so as to automatically actuate the said latch means 30 at a predetermined load in the said scraper to rotate the said scraper to a non-scraping position; and means secured to the said latch means and manually operable before the 35 said scraper has picked up the predetermined load for rotating the said scraper to the non-scraping position.
15. In a rotary scraper, the combination of: a scoop; a draft frame pivotally secured to said scoop; a stop carried by said scoop; 40 a latch bar carried by said draft frame, said latch bar being adapted to engage said stop, thus retaining said scoop in digging position; a loading lever pivotally attached to said draft frame; a link connected to said 45 loading lever and the rearward end of said latch bar; an intermediate member secured to said draft frame whereby said scraper is pulled; and a link extending between said intermediate member and said loading lever.
- 50 16. In a rotary scraper, the combination of: a scoop; a draft frame pivotally secured to said scoop; a stop carried by said scoop; a latch bar carried by said draft frame, said latch bar being adapted to engage said stop, 55 thus retaining said scoop in digging position; a loading lever pivotally attached to said draft frame; a link connected to said loading lever and the rearward end of said latch bar; an intermediate member pivotally 60 secured to said draft frame whereby said 65 scraper is pulled; and a link extending between said intermediate member and said loading lever.
- scraper is pulled; and a link extending between said intermediate member and said loading lever.
17. In a rotary scraper the combination of: a scoop having digging and carrying positions; a draft frame through which said scoop may be pulled by a tractor, said frame being extensible by the tractive pull of said tractor when said pull reaches a certain value; means for fixing said value; and means operated by the extension of said frame to move said scoop from digging to carrying position. 70
18. In a rotary scraper the combination of: a scoop having digging and carrying 80 positions; a draft frame through which said scoop may be pulled by a tractor, said frame being extensible by the tractive pull of said tractor when said pull reaches a certain value; means for fixing said value; means 85 operated by the extension of said frame to move said scoop from digging to carrying position; and means for automatically locking said scoop in carrying position.
19. In a rotary scraper the combination of: a scoop having digging and carrying 90 positions; a draft frame through which said scoop may be pulled by a tractor, said frame being extensible by the tractive pull of said tractor when said pull reaches a certain 95 value; means for fixing said value; means operated by the extension of said frame to move said scoop from digging to carrying position; means for automatically locking said scoop in carrying position; and means permitting said scoop to be moved 100 manually from digging position to carrying position.
20. In a rotary scraper the combination of: a scoop having digging and carrying 105 positions; a draft frame through which said scoop may be pulled by a tractor, said frame being extensible by the tractive pull of said tractor when said pull reaches a certain value; means for fixing said value; means 110 operated by the extension of said frame to move said scoop from digging to carrying position; and means permitting said scoop to be moved manually from digging position to carrying position. 115
21. In a rotary scraper the combination of: a scoop having digging, carrying and dumping positions; a draft frame through which said scoop may be pulled by a tractor, said frame being extensible by the tractive pull of said tractor when said pull reaches a certain value; means for fixing said value; means 120 operated by the extension of said frame to move said scoop from digging to carrying position; and means for manually disengaging said scoop from digging or carrying positions, and freeing said scoop for movement to dumping position.
22. In a rotary scraper the combination of: a scoop having digging, carrying and 125

dumping positions; a draft frame through which said scoop may be pulled by a tractor, said frame being extensible by the tractive pull of said tractor when said pull reaches a certain value; means for fixing said value; means operated by the extension of said frame to move said scoop from digging to carrying position; means for automatically locking said scoop in carrying position; and means for manually disengaging said scoop from digging or carrying positions, and freeing said scoop for movement to dumping position.

23. In a rotary scraper the combination of: a scoop having digging, carrying and dumping positions; a draft frame through which said scoop may be pulled by a tractor, said frame being extensible by the tractive pull of said tractor when said pull reaches a certain value; means for fixing said value; means operated by the extension of said frame to move said scoop from digging to carrying position; means for automatically locking said scoop in carrying position; means permitting said scoop to be moved manually from digging position to carrying position; and means for manually disengaging said scoop from digging or carrying positions, and freeing said scoop for movement to dumping position.

24. In a rotary scraper the combination of: a scoop having digging, carrying and dumping positions; a draft frame through which said scoop may be pulled by a tractor, said frame being extensible by the tractive pull of said tractor when said pull reaches a certain value; means for fixing said value; means operated by the extension of said frame to move said scoop from digging to carrying position; means permitting said scoop to be moved manually from digging position to carrying position; and means for manually disengaging said scoop from digging or carrying positions, and freeing said scoop for movement to dumping position.

25. In a rotary scraper the combination of: a scoop having digging and carrying positions; a draft frame through which said scoop may be pulled by a tractor, said frame being extensible by the tractive pull of said tractor when said pull reaches a certain value, the front end of said frame being raised by said extension thereof; means for fixing said value; and means operated by the extension of said frame to move said scoop from digging to carrying position.

26. In an automatic scraper control, the combination of: a frame; a scraper pivotally mounted in the frame; and a draft con-

nection pivotally secured to the said frame and adapted to automatically operate at a predetermined load within the scraper to rotate the said scraper to a non-scraping position.

27. In an automatic scraper control, the combination of: a frame; a scraper rotatably mounted in the frame; an arm pivotally mounted at the forward end of the said frame; an actuating lever pivotally secured at the other end of the said frame; means connecting the said arm and said lever; and means secured to the said arm for connecting the said frame with a draft implement and operable at a predetermined load in the said scraper to actuate the said lever to engage the said scraper and to rotate the same to a non-scraping position.

28. In a rotary scraper, the combination of: a scoop; a draft frame to which said scoop is pivotally attached; a control mechanism for retaining said scoop in digging position; means secured to said draft frame whereby said scraper is pulled, said means being associated with said control mechanism so as to automatically operate said mechanism and remove said scoop from digging into carrying position when said scoop is loaded.

29. In a rotary scraper the combination of: a scoop having digging and carrying positions; a draft frame through which said scoop may be pulled by a tractor; a link in said draft frame through which link tractive pull from said tractor is transmitted to said scoop, said link being misaligned an adjustable degree with the direction of said tractive pull so that a tendency is set up proportional to said tractive pull to align said link with the direction of said pull; and means, operated by said tendency of said link, to move said scoop from digging position to carrying position when said tractive pull reaches a certain value.

30. In a rotary scraper the combination of: a scoop having digging and carrying positions; a draft frame through which said scoop may be pulled by a tractor; a mechanism for moving said scoop from digging position to carrying position; and a lever receiving tractive pull from said tractor, transmitting tractive pull to said frame, and operating the aforesaid mechanism when the tractive pull received thereby reaches a given value.

In testimony whereof, I have hereunto set my hand at Los Angeles, California, this 17th day of February, 1925.

JOSEPH S. REYNOLDS.

DISCLAIMER

1,642,826.—*Joseph S. Reynolds*, Long Beach, Calif. ROTARY SCRAPER WITH AUTOMATIC ELEVATING CONTROL. Patent dated September 20, 1927. Disclaimer filed December 26, 1933, by *Olive M. Reynolds*, trustee of the Estate of Joseph S. Reynolds, deceased.

Hereby enters this disclaimer to that part of the claims in said specification which is in the following words, to wit:

“1. In a rotary scraper, the combination of: a draft frame; a scoop supporting one end of said draft frame to which said scoop pivotally attaches; a control mechanism for retaining said scoop in digging position; and an intermediate member pivotally secured to said draft frame whereby said scraper is pulled, said intermediate member being associated with said control mechanism so as to operate said mechanism and remove said scoop from digging into carrying position when said scoop is loaded.”

“6. In a rotary scraper the combination of: a scoop having digging and carrying positions; a draft frame supported at one end by said scoop through which said scoop may be pulled by a tractor, said frame being extensible by the tractive pull of said tractor when said pull reaches a certain value, the front end of said frame being raised by said extension thereof; means for fixing said value; and means operated by the extension of said frame to move said scoop from digging to carrying position.”

“9. In an automatic scraper control, the combination of: a frame; a scoop pivotally supporting one end of said frame; and a draft connection pivotally secured to the said frame and adapted to operate at a predetermined load within the scraper to rotate the said scraper to a non-scraping position.”

“11. In an automatic scraper control, the combination of: a frame; a scraper pivotally mounted within the frame and supporting one end thereof; means for connecting the said frame with a draft implement and operable at a predetermined load for rotating the said scraper in the said frame; and means for adjusting the said draft connecting means so as to regulate the load at which the said scraper is rotated.

“12. In an automatic scraper control, the combination of: a frame; a scraper pivotally mounted in the frame and supporting one end thereof; latch means secured to the frame and adapted to be engaged with the said scraper for latching the said scraper in the scraping position; means pivotally connecting the said frame with a draft implement; means pivotally connecting the said last named means with the said latch means and operable at a predetermined load for rotating the said scraper to a non-scraping position; and means associated with the said latch means for releasing the same to permit the scraper to rotate in the frame to dump the load.

“13. In a scraper of the character described, the combination of: a draft device; a scoop pivotally supporting one end of said draft device and adapted to be drawn thereby; a stop supporting member secured to said scoop substantially midway between the ends thereof; a stop secured to said member; means mounted on said draft device for holding or releasing said stop so as to permit the scoop to be held in scraping position, or released to dumping position as may be desired; and means pivotally secured to the draft device and adapted to operate at a predetermined load within the scoop to rotate the said scoop to a non-scraping position.

“14. In an automatic scraper control, the combination of: a frame; a scraper pivotally mounted within the frame; latch means secured to the frame and adapted to engage the said scraper to hold the same in the scraping position; draft means secured to the said frame; means connecting the draft means with the said latch means so as to automatically actuate the said latch means at a predetermined load in the said scraper to rotate the said scraper to a non-scraping position; and means secured to the said latch means, and manually operable before the said scraper has picked up the predetermined load for rotating the said scraper to the non-scraping position.”

“17. In a rotary scraper the combination of: a scoop having digging and carrying positions; a draft frame through which said scoop may be pulled by a tractor, said frame being extensible by the tractive pull of said tractor when said pull reaches a certain value; means for fixing said value; and means operated by the extension of said frame to move said scoop from digging to carrying position.”

“20. In a rotary scraper the combination of: a scoop having digging and carrying positions; a draft frame through which said scoop may be pulled by a tractor, said frame being extensible by the tractive pull of said tractor when said pull reaches a certain value; means for fixing said value; means operated by the extension of said frame to move said scoop from digging to carrying position; and means permitting said scoop to be moved manually from digging position to carrying position.

“21. In a rotary scraper the combination of: a scoop having digging, carrying and dumping positions; a draft frame through which said scoop may be pulled by a tractor, said frame being extensible by the tractive pull of said tractor when said pull

reaches a certain value; means for fixing said value; means operated by the extension of said frame to move said scoop from digging to carrying position; and means for manually disengaging said scoop from digging or carrying positions, and freeing said scoop for movement to dumping position."

"24. In a rotary scraper the combination of: a scoop having digging, carrying and dumping positions; a draft frame through which said scoop may be pulled by a tractor, said frame being extensible by the tractive pull of said tractor when said pull reaches a certain value; means for fixing said value; means operated by the extension of said frame to move said scoop from digging to carrying position; means permitting said scoop to be moved manually from digging position to carrying position; and means for manually disengaging said scoop from digging or carrying positions, and freeing said scoop for movement to dumping position.

"25. In a rotary scraper the combination of: a scoop having digging and carrying positions; a draft frame through which said scoop may be pulled by a tractor, said frame being extensible by the tractive pull of said tractor when said pull reaches a certain value, the front end of said frame being raised by said extension thereof; means for fixing said value; and means operated by the extension of said frame to move said scoop from digging to carrying position.

"26. In an automatic scraper control, the combination of: a frame; a scraper pivotally mounted in the frame; and a draft connection pivotally secured to the said frame and adapted to automatically operate at a predetermined load within the scraper to rotate the said scraper to a non-scraping position."

"28. In a rotary scraper, the combination of: a scoop; a draft frame to which said scoop is pivotally attached; a control mechanism for retaining said scoop in digging position; means secured to said draft frame whereby said scraper is pulled, said means being associated with said control mechanism so as to automatically operate said mechanism and remove said scoop from digging into carrying position when said scoop is loaded.

"29. In a rotary scraper the combination of: a scoop having digging and carrying positions; a draft frame through which said scoop may be pulled by a tractor; a link in said draft frame through which link tractive pull from said tractor is transmitted to said scoop, said link being misaligned an adjustable degree with the direction of said tractive pull so that a tendency is set up proportional to said tractive pull to align said link with the direction of said pull; and means, operated by said tendency of said link, to move said scoop from digging position to carrying position when said tractive pull reaches a certain value.

"30. In a rotary scraper the combination of: a scoop having digging and carrying positions; a draft frame through which said scoop may be pulled by a tractor; a mechanism for moving said scoop from digging position to carrying position; and a lever receiving tractive pull from said tractor, transmitting tractive pull to said frame, and operating the aforesaid mechanism when the tractive pull received thereby reaches a given value."
